UNITED STATES PATENT OFFICE.

CHARLES F. NEER, OF CATAWBA, OHIO.

CHECK-ROWER AND MARKER.

SPECIFICATION forming part of Letters Patent No. 349,402, dated September 21, 1886.

Application filed May 14, 1886. Serial No. 202,165. (No model.)

To all whom it may concern:

Be it known that I, CHARLES F. NEER, a citizen of the United States, residing at Catawba, in the county of Clark and State of Ohio, have invented certain new and useful Improvements in Check-Rowers and Markers, of which the following is a specification, reference being had therein to the accompanying drawings.

- 10 This invention relates to certain new and useful improvements in check-rowers and markers for use in connection with corn-planters; and it consists, essentially, first, of a shaft adapted to be actuated by the foot of the operator, and check-row mechanism combined with it and adapted to be actuated so as to doff the check-row wire from the check-row mechanism as the planter reaches the extremes of the field without the driver's dismounting; second, in providing a shaft with cam-hooks, which, when the shaft is partially rotated, act to doff the check-row wire from the pulleys of the check-row mechanism; and, third, in combining with the shaft, which is 20 adapted to be actuated by the foot of the operator, a marker, in such manner as that the marker can be shifted from one side of the planter to the other by the simple movement of the foot.
- 25 In the accompanying drawings, forming a part of this specification, and on which similar letters of reference indicate the same or corresponding features, Figure 1 represents a plan view of a corn-planter of any approved type with the seed-dropping mechanism omitted, showing my improvements applied thereto; Fig. 2, a longitudinal sectional view of the corn-planter, showing the mechanism for actuating the marker, the marker being in an elevated position; Fig. 3, a sectional view of the cross-beam of the hounds and an elevation of the post to which the marker-rope is attached; Fig. 4, a plan view of the check-row mechanism proper; Fig. 5, an end view of that mechanism; Fig. 6, a rear view of the planter-frame, showing the marker-beam and the mechanism for actuating it; Fig. 7, detached detail views of one of the cam-hooks and the bifurcated lever, and Fig. 8 a detached perspective view of a journal-bearing frame.
- 30 The letter A designates the frame-work generally of a corn-planter of any approved con-

struction, the same being mounted upon the usual wheels, B, and supplied with the tongue-hounds C, the cross-beam D of which carries the check-row mechanism. This mechanism consists of a beam, E, upon which are secured standards F and G, to which are mounted the usual grooved pulleys, H and I, between which the check-row wire is passed and supported. At or near the other or forward end of the beam E is journaled a grooved roller, J, its axis being at right angles to the axes of the rollers just described, and adjacent to which (the roller J) is a projecting hook, K, which 60 serves to maintain the check-row wire within the groove of said pulley.

Pivotedly connected with the beam E is a bifurcated lever, L, the extreme free end of which is fashioned after the manner of a fork, 70 so as to admit of the more ready entrance of the check-row wire. Also mounted in suitable bearings secured to the beam is a rock-shaft, M, having a pin, N, passing through it, to which is connected a spiral spring, O, the 75 other end of which engages the bar P. This shaft carries cam-hooks, which will be presently described, and the adjustment of the spring is such that its action is to keep these hooks normally away from the check-row 80 wire, as also to return the shaft to a normal position after the engagement of the hooks with the wire for the purpose of doffing the same.

The hooks just alluded to consist of metallic 85 plates Q, secured the one to the shaft M and the other either to that shaft or to a segment, R, which is secured to it. The hooks are substantially alike, the one mounted upon the shaft directly having a shoulder, S, as seen in 90 Fig. 7, and this shoulder acts to arrest the wire should it slide down on the hook as the hook engages the wire, as hereinafter appears. This hook, when moved in the direction of the arrow shown in Fig. 4, will engage the under 95 side of the pivoted lever L and elevate it by the time the curved portion extending from the shoulder to the hook proper will begin to engage the wire, and as the hook-cam proceeds in its rotation in the direction of the arrow shown in Fig. 7 it gradually throws the wire 100 out of the bifurcation of the lever. This action throws the wire from the pulley J, and hence frees it from that end of the check-row

mechanism proper. While this action is taking place the other hook is correspondingly moving, and is engaging the wire and slipping it past the inner end of the roller I, the movement being continued in the direction of the arrow (see Fig. 5) until the wire is entirely clear of both pulleys H and I. This effects a disconnection of the wire with the planter. This action is brought about as the machine reaches the extreme of the field, whereby the machine can turn around and be driven in the opposite direction without disconnecting the wire by hand.

It has already been stated that shaft M is provided with a segment, R. This segment is grooved, and a chain, T, is connected with its upper inner portion and passes over it, and thence inwardly to the pulley U. Another chain T connects the segment R at the other side of the machine also with the pulley U, the points of connection of the chains T being at diametrical points. This pulley is mounted upon a longitudinally-placed shaft, V, having bearings in the frame of the planter, and is provided with a foot-lever, W, located in convenient reach of the operator's foot. It will be seen, therefore, that by depressing the lever W a partial rotation will be given the shaft V and the pulley U, and through the chains T a like movement will be imparted to the shaft M, and the action above described of the hooks upon the wire brought about.

The advantages of being able to disconnect the check-rower mechanism from the wire without leaving the machine or even stopping it are obvious. The shaft V terminates at its rear end in a crank, X, the outer end of which is bent to form a socket, Y, for the reception of the marker-beam, while the body of the crank is curved at Z, as seen in Fig. 6, for the purpose of preventing the marker from tipping in the direction of the seat as it is elevated. This shaft is further provided with a gear-wheel, a, which gears with a like wheel, b, mounted upon a shaft, c, the rear end of which terminates in a crank constructed in duplication of the crank X. A metallic bearing-frame, d, (seen more clearly in Fig. 6,) constitutes a bearing for the forward end of the shaft c, and also a bearing for the shaft V at a point just forward of the gear-wheel a. This frame also forms in part the rear bearings for the shafts V and c. Pivoted in two posts, e, extending from said frame d is a pawl, f, the heavier end of which stands normally engaged with the gear-wheel b, while by putting the foot upon the other end this engagement is broken. The purpose of this pawl is to lock the cranks in any set position—as, for instance, in a vertical position, as seen in Fig. 6—whereby the marker-beam is held in returning to and from the field and while turning round in the field.

The marker consists of the beam g, swiveled at h, and provided at its free end with a marker, i, which is connected by a stay-rope, j, to a post, k, secured to the tongue-frame.

The function of the marker is, as usual, to designate the point over which the center of the machine shall be driven in making the return trip.

It will be observed that the act of actuating the check-rower mechanism in the manner above described also actuates the marker in either direction. If at the side of the machine, as seen in Fig. 1, then a depression of the lever W through the shaft V and the crank X will elevate the marker, and at the same time bring the opposite crank to a vertical position for the purpose of receiving the marker and letting it down on the opposite side. The stay-rope swings over and above the operator's head. The pawl f is of course tripped by the foot of the operator, so as to allow the gears to rotate.

By means of this invention it will be observed that the operator is saved the following labor and loss of time: the getting off the planter at the end of a row; the detaching the wire from the check-rower; walking to the opposite side of the planter and adjusting the marker to the opposite position; getting on the planter, and turning the team and planter around in order to start back; getting off the planter again to place the marker in position, and walking to opposite side of planter and arranging the check-rower wire for starting.

All of the above-named operations are avoided by the improvements herein described, as the planter needs only to be turned and the wire arranged for starting. In machines as heretofore constructed only a part of these manual operations have been saved. A hand-lever might be used in lieu of the foot-lever W.

Having thus fully described my invention, what I claim as new, and desire to secure by Letters Patent, is—

1. The combination, with a corn-planter provided with a shaft adapted to be actuated by the foot, of a check-rower mechanism, including a rock-shaft connected with the first-named shaft and provided with hooks which throw the wire from the pulleys.

2. The combination, with a corn-planter and a rock-shaft having a foot-lever and a pulley, of a check-rower having a rock-shaft carrying a segment connected with the said pulley and provided with hooks to throw the wire from the check-rower pulleys, and a spring to return the check-rower shaft to its normal position.

3. The combination, with a corn-planter and a rock-shaft having a foot-lever and a pulley, of a check-rower having a rock-shaft provided with a segment connected to said pulley by a chain, and with cam-hooks which engage the wire and dislodge it from the check-rower pulleys, and with a spring to return the shaft to its normal position.

4. The combination, with the pulleys of a check-rower, of a rock-shaft provided with cam-hooks adapted when the shaft is partially rotated to engage the wire and dislodge it from said pulleys.

5. The combination, with a beam carrying

- grooved pulleys and a pivoted bifurcated lever, of a rock-shaft and the cam-hooks mounted thereon and adapted, one to engage the wire directly and the other the pivoted lever and 5 then the wire when the shaft is partially rotated, to dislodge the wire from said pulley, and the spring to return the shaft to its normal position.
6. The combination, with a beam having 10 grooved pulleys at one end, and a grooved pulley placed at right angles to said pulleys at the other end, a hook, and a pivoted lever, of a rock-shaft, the spring to hold it and return it to the normal position, a segment by 15 which it is operated, and cam-hooks carried by the shaft and adapted, the one to engage the wire directly and the other the said lever and then the wire, to dislodge the wire from the pulleys.
- 20 7. The combination, with a rock-shaft mounted on a corn-planter, of the check-rower mechanism having a rock-shaft, and a connection between said shaft, whereby the actuation of the first-named actuates the last-named shaft.
- 25 8. The combination, with a rock-shaft, of cam-hooks adapted to engage and dislodge the wire.
9. The combination, with a corn-planter, of a rock-shaft having a foot-lever, a crank, and a gear-wheel, and another shaft having in it a 30 meshing gear-wheel and a crank, and a pivoted marker adapted to be elevated and lowered by said cranks.
10. The combination, with a planter, of a rock-shaft having a foot-lever and gear-wheel, 35 and a crank curved in the body and bent to form a socket at the end, and another shaft having a like crank and an intermeshing gear-wheel, a locking-pawl, and the pivoted marker adapted to be lifted from side to side and held 40 up by said crank.
11. The combination, with a corn-planter and an actuating crank-shaft, and a crank-shaft geared thereto, of a check-rower mechanism provided with a rock-shaft carrying hooks constructed to dislodge the wire, and connected with the operating-shaft, and a pivoted marker adapted to be lifted and lowered by said crank-shafts.
12. The combination, with a corn-planter, 50 of the U-shaped bearing-frame secured thereto and the crank-shafts mounted in said frame.

In testimony whereof I affix my signature in presence of two witnesses.
